LOUNGE CHAIR

Eleanor M. Forbes, San Francisco, Calif.

Application September 30, 1957, Serial No. 47,928

Term of patent 14 years

(Cl. D15—1)

I claim:

The ornamental design for a lounge chair, as shown.
